UNITED STATES PATENT OFFICE.

AXCEL C. JACOBSON, OF SAN FRANCISCO, CALIFORNIA.

SAWING MACHINE.

Application filed January 18, 1926. Serial No. 81,939.

This invention relates to sawing machines and particularly to an improved power operated portable saw. My improved saw comprising this invention is mounted for free traveling and swinging movement to the parts to be sawed, is power driven by an electric motor, which motor is so mounted as to counterbalance the saw, and is provided with automatic switch means for operating the motor and saw only when the saw is brought to the working position. It is the primary object of my invention to provide an improved sawing machine of this type which is particularly adapted for use as a butcher's saw.

My improved machine is also constructed in a manner adapting the saw and its supporting parts to be adjusted vertically to the most convenient operative position, and the traveling carriage which supports such parts is also provided with means for securing the same against movement on its supporting track when desired. It is another object of my invention to provide an improved sawing machine of this type and having these improved and novel features which render the same more efficient and convenient in operation.

In the accompanying drawing I have shown certain specific embodiments of my invention, but it will be understood that the invention can be otherwise embodied and that the drawings are not to be construed as defining or limiting the scope of the invention, the claims appended to this specification being relied upon for that purpose.

Referring to the figures of the drawing:

Figure 1 is a perspective view of my improved sawing machine in operation.

Figure 2 is an enlarged perspective view of the machine.

Figure 3 is a side elevation thereof partially in section.

Figure 4 is a side elevation of the carriage and yoke.

Figure 5 is a fragmentary plan sectional view of the machine, taken on line V—V of Fig. 3.

In the drawing, 1 indicates an overhead track adjustably mounted on a pair of supporting posts 2 secured to the ceiling. My improved sawing machine is hung from a carriage 3 traveling on this track. The carriage comprises a body portion supported by rollers 4 and having a downwardly extending sleeve 5. A forked yoke 6 has an

upwardly extending shank 7 adjustably mounted in the sleeve 5 and adapted to be held therein by a set screw 8.

The operating parts of my machine are mounted on an arm 9 pivotally supported in the yoke on trunnions 10. This entire arm is hollow and provides a housing for the operating parts. An electric motor 11 is mounted in the enlarged end 12 of the arm at one side of the trunnions and a circle saw 13 is mounted on a transverse shaft 14 in the other end of the arm. A shaft 15 and bevel gears 16 operatively connect the motor to the shaft 14. A fixed guard 17 and a movable guard 18 surround the saw as described in my co-pending application Serial No. 81,940, filed January 18, 1926. An operating handle 19 is secured to the saw end of the arm.

The motor 12 is controlled by a switch within a box 20. This switch is normally closed so as to operate the motor. The relative weight of the motor is such that the arm normally assumes the position illustrated in Figure 2. In such position, the switch button 21 engages against a resilient stop 22 on the yoke 6, whereby the button is forced inwardly and opens the switch. Thus, when the saw is not in use, it tilts upwardly in a manner moving the saw well above the work table and automatically opens the motor circuit. A socket is provided in the box 20 for receiving the electrical connection 23.

Normally, the carriage 3 is free to move along the track 1. It may be desired at times to prevent such movement and to secure the carriage in a definite position on the track. A plate 24 extends over the top of the track between the rollers 4 and is secured to the upper end of a rod 25. This rod extends downwardly through a lug 26 on the yoke. A thumb nut 27 is threaded to the rod beneath the lug. By adjusting this nut, plate 24 can be drawn into tight frictional engagement with the track and thereby hold the carriage against movement.

The operation of the machine is believed to be obvious. Normally, the machine is in the position shown in Fig. 2, wherein the saw is well above the table, thus leaving the table free for arranging the meat thereon. When a bone is to be sawed, the operator grasps the handle 19 and pulls the saw forwardly and downwardly, the free movement of the carriage on the track permitting the saw to be properly placed laterally. As the

saw is drawn downwardly, the switch button 21 leaves the stop 22, whereupon the switch automatically closes and starts the motor. When the saw reaches the work, it has attained sufficient momentum to efficiently perform the sawing operation. The operator moves the guard 18 upwardly when drawing the saw downwardly, by drawing the finger latch 28 outwardly as defined in my said co-pending application. When the sawing operation is completed, the saw is released and automatically tilts upwardly and becomes inoperative. It will be understood that the several parts of the machine can be adjusted to the desired height and positions by the means heretofore described.

Having thus described my invention, what I claim is:

1. A sawing machine, comprising the combination of a downwardly extending yoke having angularly disposed lower ends with an upwardly open recess in each, means supporting the yoke for free movement forwardly and backwardly, an arm pivotally supported in the yoke by trunnions seated in the recesses, a motor on the arm at the rear side of the yoke, a rotary saw on the arm at the front side of the yoke, an operative

driving connection from the motor to the saw, the arm being so balanced that the motor normally raises the saw to the inoperative position, and a handle on the saw end of the arm for pulling the arm and saw into the operative position, the arm being removable from the yoke by raising the trunnions from the recesses.

2. A sawing machine, comprising the combination of a yoke, means supporting the yoke for lateral movement, an arm extending between the two legs of the yoke and pivotally supported thereby on trunnions at opposite sides of the arm, a motor on the arm at the rear side of the yoke, a rotary saw on the arm at the front side of the yoke, an operative driving connection from the motor to the saw, a normally closed switch in the motor circuit mounted directly on the motor, an extension on the lower end of the yoke, the arm being so balanced that the motor normally raises the saw to the inoperative position and the extension being so located that it is then engaged by and opens the switch, and a handle on the saw end of the arm for pulling the arm and saw into the operative position.

AXCEL C. JACOBSON.
